UNITED STATES. PATENT OFFICE.

WILLIAM RANDLE, SR., OF FORT WORTH, TEXAS.

COMBINED HAY-PRESS AND HORSE-POWER.

SPECIFICATION forming part of Letters Patent No. 291,082, dated January 1, 1884.

Application filed September 17, 1883. (No model.)

To all whom it may concern:

Be it known that I, WILLIAM RANDLE, Sr., a citizen of the United States, residing at Fort Worth, in the county of Tarrant and State of Texas, have invented certain new and useful Improvements in Combined Hay-Press and Horse-Power; and I do hereby declare that the following is a full, clear, and exact description of the same, reference being had to the annexed drawings, making a part of this specification, and to the letters and figures of reference marked thereon.

Figure 1 of the drawings is a perspective view of my invention; Fig. 2, a longitudinal section of the hay-press; Fig. 3, a horizontal section thereof; Fig. 4, a detail view, showing the construction of one of the hasps and the recess in the door with which it engages.

The present invention has relation to certain new and useful improvements in baling-presses for hay or other material, and refers more particularly to horizontal presses wherein is employed a horizontal plunger operated by cords and pulleys connected with a suitable horse-power.

The object of the invention is to provide a simple and effective baling-press that may be easily operated by horse-power and the bale readily removed from the press; and it consists in the several details of construction, substantially as shown in the drawings, and hereinafter described and claimed.

In the accompanying drawings, A represents the horizontal press-box, provided with the guide-extension B for the plunger C. The press-box A has hinged side doors, D E, opening downward, and to the top of said box are hinged doors F G, the former opening lengthwise, and the latter opening transversely of the box. The door D is provided with staple-arms a, with which engage hinged hasp-arms b, projecting from the door E and extending over the door F, while the door G is provided with similar hasp-arms, c, to engage with stationary staple-arms d, the several staple and hasp arms being fastened together by suitable keys, e. The door F has connected to it metal hasps f, which extend over the edge of the door, and are formed with downwardly-projecting flanges g, said flanges entering recesses h after having passed over the staples j, secured to the door G, thereby securely connecting to-

gether the two top doors of the press, as more clearly shown in Fig. 4. The flanges g of the hasps f, in connection with the recesses h, into which they enter, make together a very firm lock for the doors, and the edges of the hasps being flanged gives them greater strength and renders them less liable to become bent. The manner of securing the several doors together 55 renders them strong and durable and capable of withstanding the great outward pressure necessary in the process of baling, while the doors can be opened very quickly and with comparatively little trouble. The plunger C 60 is provided with a horizontal beam, H, its ends extending out through the sides of the extension B of the press. This extension B is provided with ways or tracks i k, over which fit the recesses l upon the upper and lower edges 65 of the beam H. By the above construction the beam H will be prevented from moving laterally, and therefore guided in a straight line, carrying the plunger with it against the material in the box A. The beam H is connected to a suitable windlass, I, by cord or rope m, said windlass having its bearings in uprights n at the end of the extension of the press. These uprights n and horizontal braces p fit over the reduced ends r of the extension 70 B, and are held thereon by keys s, thus admitting the ready removal of the uprights and braces, and allowing the plunger C, with its beam, to be removed when required for any purpose. The windlass I is provided with a 75 suitable crank-handle, J, for turning it to draw the plunger C back in position after baling the hay. A rope or cord, t, passes around the front end of the press and extends backward to the beam H, after which the ends of 80 the rope or cord are brought around grooved pulleys u at the ends of the beam and forward, where they are connected to a second rope or cord, v, by hooks or other suitable means. The cord or rope v is wound around an upright 85 windlass, K, supported in a suitable frame, L, and operated by horse-power in the ordinary manner. The windlass K has seats w extending spirally around the shaft thereof, and diminishing in diameter as they extend 90 upward, so as to equalize the power as the plunger is being forced against the hay or other material in the box A.

To the upper portion of the extension B of

the press and at its sides are pivoted weighted dogs M, so that after the plunger C has been brought forward against the hay in the box A its greatest distance the dogs M will automatically fall to the position to firmly lock or hold the plunger in place by bearing against the cross-beam H, shoulders y being formed on the dogs for that purpose.

Having now fully described my invention, to what I claim as new, and desire to secure by Letters Patent, is—

1. In a baling-press, the combination, with the plunger C, of the box A, provided with hinged side doors, D E, and the several staple-arms b c and hasp-arms a d and keys e, and the hinged top doors, F G, the latter having the staple j and the former the metal hasps f, having downwardly-projecting flanges g, adapted to enter recesses h in the opposite hinged door, substantially as and for the purpose set forth.

2. The combination, with the press-box A, having its several hinged doors and means for fastening them closed, of the plunger C, beam H, formed with recesses l, and the extension B, having ways or tracks i k, the windlass I, and cord or rope m, substantially as and for the purpose specified.

3. The press-box A, having its hinged doors and fastenings, and the extension B, provided with ways or tracks i k, and notched weighted dogs M, in combination with the plunger C, cross-beam H, having recesses l, fitting over the ways or tracks, and provided with the pulleys u, the cord or ropes t v, and windlass K, substantially as and for the purpose described.

4. A baling-press consisting of the box A and hinged doors D E F G and its fastening devices, the extension B, having tracks or ways i k, notched weighted dogs M, windlass I, and cord or rope m, the plunger C, cross-beam H, having recesses l and pulleys u, cords or ropes t v, and the windlass K, provided with spiral seats w, all constructed and arranged to operate substantially as and for the purpose set forth.

In testimony that I claim the above I have hereunto subscribed my name in the presence of two witnesses.

WILLIAM RANDLE, SR.
